UNITED STATES PATENT OFFICE.

MARTIN T. CONVERY, OF PHILADELPHIA, PENNSYLVANIA.

HYDROCARBON-BURNER.

1,117,165.

Specification of Letters Patent. Patented Nov. 17, 1914.

Application filed April 18, 1914. Serial No. 832,715.

To all whom it may concern:

Be it known that I, MARTIN T. CONVERY, a citizen of the United States, residing at Philadelphia, in the county of Philadelphia and State of Pennsylvania, have invented 5 certain new and useful Improvements in Hydrocarbon-Burners, of which the following is a specification.

My invention relates to improvements in 10 hydro-carbon burners, the object of the invention being to provide an improved burner in which the oil is forced to spread out into a thin sheet or spray which is thoroughly atomized by steam and commingled with the 15 oxygen of the air to produce a highly combustible and economical fuel.

A further object is to provide improved 20 means for maintaining the nozzle of the oil pipe free from obstruction and without dismantling the burner.

A further object is to provide an improved burner of the character stated of extremely simple, inexpensive construction, 25 strong and durable in use.

With these and other objects in view, the 30 invention consists in certain novel features of construction and combinations and arrangements of parts as will be more fully hereinafter described and pointed out in the claims.

In the accompanying drawings: Figure 1 is a view in longitudinal vertical section 35 illustrating my improvements. Fig. 2 is a view in horizontal section partly in elevation on the line 2—2 of Fig. 1. Fig. 3 is a view in vertical transverse section on the line 3—3 of Fig. 1. Fig. 4 is a view in longitudinal section on an enlarged scale of the oil distributing nozzle. Fig. 5 is a view in end elevation of Fig. 1, and Fig. 6 is a fragmentary 40 view in section on the line 6—6 of Fig. 1.

1 represents my improved burner casing which is of general truncated conical form having at its smaller end, a cylindrical projection 2 adapted to be positioned through 45 an opening 3 in a supporting wall 4 so as to direct the flame into the furnace or other fire box.

The casing 1 is formed of a single casting 50 having integral perforated ears 5 for the reception of bolts 6, said bolts projected through the wall 4 and secured by nuts 7 to clamp the burner casing in position.

The outer larger end of the casing 1 is 55 made with an integral hollow steam head 8 located centrally with respect to the end of

the casing, and having an inlet passage 9 extending to the side of the casing and adapted to be connected to a steam supply pipe 10. The head 8 and the inlet 9 are strengthened 60 by a longitudinal web 11 inside the casing. This end of the casing, entirely around the head, is open for the admission of air, and the head is formed with a central tube 12 in which a burner tube 13 is secured by a set 65 screw 14. This burner tube 13 extends into the casing 1, is located centrally in the casing, and terminates at its inner end short of the inner end of the casing.

In the extreme inner end of the burner 70 tube, I locate my improved nozzle 15 which is rigidly fixed in the end of the burner tube in any approved manner. This nozzle has a cylindrical portion 16 fitting within the burner tube, and around this cylindrical 75 portion, at the outer end of the nozzle, an annular shoulder 17 is provided which bears against the extreme end of the burner tube.

The outer end of the nozzle is formed 80 with a lip 18 which extends transversely throughout the width of the nozzle, and has an inclined surface 19 against which the oil is directed through a passage 20 in the nozzle.

It will be noted that the beveled surface 85 19, at its highest point, is in an approximate alignment with the highest point of passage 20, and the lowest point of the beveled surface is in line with the lowest point of the passage 20, yet a small space 21 is provided 90 between the lower end of the inclined surface and the passage, so that the oil is permitted to escape from the end of the tube before it strikes the inclined surface. This gives to the oil an impact against the inclined surface of the lip which tends not only to spread it into a thin sheet, but to divide the globules so that they readily commingle with the steam and air. 95

The extreme inner end of the passage 20 has a flared mouth 22, so as to direct the end of a cleaning rod 23 into the passage. This cleaning rod 23 is located centrally in the burner tube 13, and projects through a coupling 24 on the outer end of the burner tube. This coupling 24 is of general T-shape, and has a curved passage 25 for the oil, one end of this passage communicating with the burner tube, and the other end with the supply pipe 26. 100

The coupling 24 has a longitudinal passage 27 for the guidance of the rod 23, and 110

a stuffing box 28 is provided in the end of the coupling to form a tight packing around the rod and prevent leakage of oil at this point.

8 The outer end of the rod may, of course, be operated in various ways. I have illustrated the same as having a handle portion 29 projecting at right angles to the rod, and said handle having an eye 30 at its free end connected by a chain 31 with a ring 32 located in a groove 33 around the coupling 24. This chain serves to hold the parts in place, but permits the rod to be moved longitudinally at any time desired to clean out the nozzle passage 20.

16 It will be noted that the steam distributing head 8 is provided at its inner end around the burner tube with a circular series 20 of discharge orifices 34, so that the steam in the head performs two functions. First, 25 its heat is imparted to the oil, tending to generate the oil into vapor or at least heating the oil so that it is more readily atomized when it commingles with the steam. Secondly, the steam is discharged through 30 the orifices in a finely divided condition, and acts as an injector to draw the air into the wide mouth or larger end of the casing, so that when the steam and air reach the oil, they will be thoroughly commingled and 35 form a highly combustible mixture.

If the flow of oil should become impaired, the rod 23 can be readily operated to clean out the passage without dismantling the 35 burner, and by positioning the lip 18 slightly beyond the end of the passage 20, any particles which accumulate in the passage can be forced out of the same without difficulty.

40 Various slight changes might be made in the general form and arrangement of parts described without departing from my invention, and hence I do not limit myself to the precise details set forth, but consider 45 myself at liberty to make such changes and alterations as fairly fall within the spirit and scope of the appended claims.

Having thus described my invention, what I claim as new and desire to secure by Letters Patent is:

1. A hydro-carbon burner comprising an air inlet casing, a steam head located centrally at one end of the casing and having a series of discharge orifices, said steam head 55 having a central tube, a burner tube extending through the tube in the steam head, means for directing oil into the outer end of the burner tube, and a distributing nozzle in the inner end of the burner tube, substantially as described.

2. A hydro-carbon burner comprising an air inlet casing, a steam head located centrally at one end of the casing and having a series of discharge orifices, a burner tube extending through the steam head, means for

directing oil into the outer end of the burner tube, a distributing nozzle in the inner end of the burner tube, said nozzle having a transverse lip at its outer end, said lip having an inclined inner face against which the oil is directed, substantially as described.

3. A hydro-carbon burner comprising a truncated conical air inlet casing, a circular hollow steam head integral with the outer end of the casing and located centrally relative to the casing, said steam head having a circular series of discharge orifices in its inner end and having a tubular passage therethrough, a burner tube secured in the tubular passage in the head and projecting 75 into the casing, means for supplying oil to the outer end of the tube, and a nozzle secured to the inner end of the tube, substantially as described.

4. A hydro-carbon burner comprising a truncated conical air inlet casing, a circular hollow steam head integral with the outer end of the casing and located centrally relative to the casing, said steam head having a circular series of discharge orifices in its inner end and having a tubular passage therethrough, a burner tube secured in the tubular passage in the head and projecting into the casing, means for supplying oil to the outer end of the tube, a nozzle secured to 85 the inner end of the tube, said nozzle having a restricted passage therethrough, and a rod mounted in the burner tube and adapted to be moved longitudinally through said last-mentioned passage, substantially as described.

5. A hydro-carbon burner comprising an air inlet casing, a steam head at the outer end of the casing, a burner tube projecting through the steam head, a nozzle in the inner end of the burner tube having a restricted passage therethrough, a coupling on the outer end of the burner tube, an oil supply pipe communicating with the coupling and directing oil into the tube, a stuffing box in the outer end of the coupling, and a rod located in the tube and projecting through the stuffing box, said rod adapted when moved longitudinally to clean out the passage in the nozzle, substantially as described.

6. A hydro-carbon burner comprising an air inlet casing, a steam head at the outer end of the casing, a burner tube projecting through the steam head, a nozzle in the inner end of the burner tube having a restricted passage therethrough, a coupling on the outer end of the burner tube, an oil supply pipe communicating with the coupling and directing oil into the tube, a stuffing box 120 in the outer end of the coupling, a rod located in the tube and projecting through the stuffing box, said rod adapted when moved longitudinally to clean out the passage in the nozzle, an arm on the outer end of said 125 stuffing box, and a rod secured to the outer end of the coupling and extending through the stuffing box and the arm, substantially as described.

rod, and a flexible device connecting said arm with the coupling, substantially as described.

7. A hydro-carbon burner comprising an air inlet casing of general truncated conical form having a cylindrical projection at its smaller end adapted to be projected through the wall of a furnace, said casing having integral perforated ears adapted to be secured to the walls of the furnace, said casing at its outer larger end having an integral hollow steam head with an integral web con-

necting the web with the inner face of the casing, and a burner tube projecting through the head into the casing, substantially as described. 15

In testimony whereof I have signed my name to this specification in the presence of two subscribing witnesses.
